UNITED STATES PATENT OFFICE.

WILLIAM L. DE REMER, OF CHICAGO, ILLINOIS.

TIE-PLATE.

No. 856,396.

Specification of Letters Patent.

Patented June 11, 1907.

Application filed February 23, 1907. Serial No. 358,904.

To all whom it may concern:

Be it known that I, WILLIAM L. DE REMER, a citizen of the United States, residing in Chicago, in the county of Cook and State 5 of Illinois, have invented certain new and useful Improvements in Tie-Plates of which the following is a specification.

This invention relates to that class of tie-plates having a grooved or ribbed upper face 10 and provided with ribs on its under side extending at an angle with relation to the upper ribs or transversely of the plate for preventing the plate and thereby the rail supported thereon from slipping or moving longitudinally upon the tie.

The principal object of the invention is to provide a simple, economical and efficient tie-plate.

A further object is to provide a tie-plate of 20 minimum weight and maximum strength and provided with integral depending or bottom rib portions adapted to prevent the longitudinal movement or slipping of the plate upon the tie and form substantially the load 25 bearing bottom surface portion of the plate beneath the rail, the top ribs being adapted to strengthen the plate longitudinally, whereby longitudinal depending flanges may be dispensed with and the desired adhesion or 30 security of connection with the tie afforded without unnecessarily cutting into or injuring the fibers thereof.

A further object is to provide a tie-plate formed of rolled metal, having a grooved or 35 ribbed upper face and bottom load-supporting and rail retaining ribs so formed that the load is evenly distributed upon the bottom surface portion of the plate formed by such ribs, such ribs forming substantially the entire 40 load supporting bottom surface of the plate, and the top and bottom ribs being so constructed and arranged that plates of various widths and each having the same top and bottom contour or configuration, or arrangement of ribs may be rolled by the same 45 rolls and cut from the same strip of metal.

Other and further objects of the invention will appear from an examination of the drawings and the following description and 50 claims.

The invention consists in the features, combinations and details of construction hereinafter described and claimed.

In the accompanying drawings Figure 1 is 55 a plan view of a tie-plate constructed in accordance with my improvements, showing

the bottom diagonal ribs in broken lines extending at an angle with relation to the top ribs; Fig. 2, a longitudinal sectional view in elevation taken on line 2 of Fig. 1, looking in the direction of the arrow, and Fig. 3, a transverse sectional view in elevation taken on line 3 of Fig. 1 looking in the direction of the arrow, or toward the rail retaining shoulder.

In constructing a tie-plate in accordance with my improvements I provide a main body portion *a* formed preferably of rolled metal and of sufficient length to extend beneath and transversely beyond the sides of a track rail to be mounted thereon, so as to form a support for such rail and protect the tie. Each plate is provided with perforations *b* and *c* arranged at suitable intervals and preferably in such position that those on the outer side of the rail are in staggered relation to those on the inner side. A rail retaining shoulder *d* extends transversely across the upper side of the plate in position to engage the outer edge of the flange of the rail when in position. The outer spike holes *c* may extend through the rail retaining shoulder and are reinforced thereby. The upper side of the plate is provided with a series of ribs *e* which extend from the inner end of the plate to the transverse rail retaining shoulder or diagonally upon the upper side of the plate. These ribs extend transversely with relation to the rail and longitudinally of the plate to such an extent as to afford the required longitudinal rigidity, and thus enable longitudinally extending bottom flanges which would cut deeply into the fibers of the tie to be dispensed with. Said ribs are also at an oblique angle with relation to the longitudinal center or length of the plate, so that they give the plate an amount of transverse rigidity which is very desirable. Bottom ribs *f* upon the under side of the plate extend diagonally across the plate and at an angle— preferably almost or quite at right angles with relation to the upper ribs, as indicated in broken lines in Fig. 1. They thus supplement the upper ribs in strengthening the plate both longitudinally and transversely. In short they strengthen the plate in directions substantially at right angles to the directions in which it is given its greatest strength by the upper ribs, so that by the two sets of ribs (upper and lower) extending substantially at right angles to each other the plate is given great rigidity and strength in

the desired directions, coupled with the advantages of lightness and economy of construction due to the use of the minimum amount of material. It is very desirable that these advantages be obtained and the plate provided with means for preventing it from moving longitudinally upon the tie, or slipping with the rail under the great weight which it is required to support, and also that this be accomplished in such a manner as to enable flanges which sink deeply into the tie to be dispensed with. The bottom ribs are therefore made of greater width than depth, each forming a slightly inclined load-bearing bottom surface portion *g* and having a preferably upright side face *h* on the side toward the outer end of the plate of only sufficient depth to prevent the plate, when properly mounted and secured to the tie, from moving longitudinally and give the ribs the required strength. The slightly inclined bottom face of each bottom rib extends preferably from the outer edge or upright side of such rib to the outer upright side of the next adjacent rib and toward the inner end of the plate so that the entire load-bearing bottom face of the plate beneath the rail is formed by said bottom ribs, the same being so constructed that the weight of the load is evenly distributed over every part of the bottom surface formed by said bottom ribs. A flat bottom surface portion *i* may be provided at either or both ends of the plate on the outside of the ribbed portion, or laterally beyond the sides of the rail *k*.

The tie-plate thus formed is adapted to be rolled efficiently and economically, and any desired number of plates of unequal or various widths may be rolled by the same rolls and yet have the same top and bottom contour, configuration or arrangement of ribs, and the required strength in proportion to the width of each plate respectively.

I claim:

- 45 1. A tie-plate having on its upper side a series of ribs, and having on its under side a series of retaining ribs extending at an angle with relation to the upper ribs.
- 50 2. A tie-plate having on its upper side a series of ribs extending lengthwise of the plate at an oblique angle with relation to its longitudinal center, and having on its under side a series of ribs extending at an angle with relation to such upper ribs.
- 55 3. A tie-plate having on its upper side a series of ribs, and having on its under side a series of retaining ribs extending obliquely with relation to such upper ribs.

4. A tie-plate provided with spike holes therethrough and having on its upper side a series of ribs extending obliquely of the plate between the spike holes, and on its under side a series of ribs extending obliquely with relation to such upper ribs. 60

5. A tie-plate having on its upper side a transverse shoulder and a series of ribs extending obliquely with relation to such shoulder, and having on its under side a series of ribs extending at an angle with relation to the upper ribs. 65

6. A tie-plate provided with spike holes therethrough and having on its upper side a transverse shoulder and a series of upper ribs extending at an angle with relation to such shoulder, and having on its under side a series of retaining ribs extending at an angle with relation to the upper ribs. 70

7. A tie-plate having on its under side a series of retaining ribs extending obliquely of the plate and each having an upright side face in the direction of one end of the plate and a bottom surface portion extending upward and at an incline in the direction of the opposite end of the plate. 75

8. A tie-plate having ribs on its upper side, and provided with a series of retaining ribs on its under side extending at an angle with relation to such upper ribs and each having an inclined bottom surface portion. 80

9. A tie-plate having on its upper side a transverse shoulder and a series of ribs extending obliquely with relation to such shoulder, and having on its under side a series of ribs each provided with an inclined bottom surface portion and extending obliquely with relation to such upper ribs. 85

10. A tie-plate having on its upper side a transverse shoulder and ribs extending at an angle with relation to such shoulder, and provided on its under side with a series of retaining ribs extending at an angle with relation to the upper ribs and each having an inclined bottom surface portion and an upright side face. 90

11. A tie-plate having spike holes therethrough, and provided with a series of ribs on its upper side, and having on its under side a series of ribs the bottom surface portions of which form the entire load bearing bottom surface portion of the plate between the spike holes. 95
